Inventor,

George Colvin Kennedy

UNITED STATES PATENT OFFICE.

GEORGE COLVIN KENNEDY, OF WATERLOO, IOWA.

MEANS FOR VARYING THE AREAL DELIVERY OF ROSE-HEADS.

1,271,719.

Specification of Letters Patent.

Patented July 9, 1918.

Application filed April 12, 1917. Serial No. 161,655.

To all whom it may concern:

Be it known that I, GEORGE COLVIN KENNEDY, a citizen of the United States of America, and a resident of Waterloo, Black Hawk county, Iowa, have invented certain new and useful Improvements in Means for Varying the Areal Delivery of Rose-Heads, of which the following is a specification.

My invention relates to improvements in means for varying the areal delivery of rose-heads, and the object of my improvement is to combine with a sprinkling-device or the like, adjustable means adapted to both variably restrict the area of the delivery surface and permit the controlling of the direction of the rose-jet thereof.

This object I have accomplished by the means which are hereinafter described and claimed, and which are illustrated in the accompanying drawings, in which:

Figure 1 is a horizontal section of a rose-head, taken on the line *c-d* of Fig. 3, with the division contrivance therefor shown in one position therein.

Fig. 2 is a like view of the rose-head, with the division-contrivance shown in another position.

Fig. 3 is a vertical central section of said rose-head and division contrivance, taken on the line *a-b* of said Fig. 1.

Fig. 4 is a diminished plan view of said device, with parts broken away to disclose the division contrivance seated to restrict the discharge to one-half of the area of the rose-head.

Fig. 5 is a like view of the device, showing the division contrivance set to restrict the discharge to one-quarter of the area of the rose-head.

Similar numerals of reference denote corresponding parts throughout the several views.

The dome-shaped rose-head 6 has a large number of small delivery perforations 7 distributed evenly over it, and is interiorly threaded at its lower end to be secured removably and adjustably upon a basal casting 1, the latter having a circumferential thread 4.

The base 1 has an integral curved nipple 2, whose orificed end 3 has an interior thread to removably receive a threaded coupling on a hose 12, and the orifice 3 may open into any part of the rose-head 6, but is

shown eccentrically placed in order to permit of the central locating of the division contrivance.

An integral depending spike 5 may be provided on the lower face of the base 1 to fix the same to the ground, but this may be omitted when such a fastening-means is not desired.

The division contrivance is placed upon the upper face of said base 1, and comprises a diametral plate 9 whose upper edge is curved to conform to the inner wall of the rose-head and fit tightly thereagainst when the parts are clamped together. The plate 9 may have an angularly projecting part 9' to subdivide the interior space of the rose-head on that side. An interiorly threaded socket 10 in the division contrivance 9 registers with an orifice 8 in the rose-head, and a thumb-screw 11 has its threaded spindle passed through the orifice 8 into the socket 10, and when rotated tightly clamps the upper edge of the parts 9 to the rose-head preventing leakage therebetween. When the part 9 is removed, the screw may remain to close the orifice 8.

The base 1, when screwed up, fits the bottom of the division contrivance to prevent leakage therebetween.

The division contrivance 9 may be mounted in the rose-head 6 in the position shown in Fig. 2 to cut off one-half of the spraying area, or reversed, as shown in Fig. 1, where the part 9' cuts off all but one-fourth of the spraying area, the base 1 being then screwed on, and the thumb-screw employed to clamp the parts together.

In Fig. 4, the division contrivance is shown in use to cut off one-half the spraying area of the rose-head at the edge of a walk or boundary line 13, so as not to cast any water upon the walk or across the boundary.

In Fig. 5, the division contrivance 9 is reversed and the device placed at the angle of a walk, boundary or building 13-14, so that spray is delivered only within said angle. The division contrivance may be easily removed, when it is desired to use the entire spraying area of the rose-head.

The device may be differently formed, divided, proportioned, or separably secured in its parts, without departing from the principle of this invention.

Having described my invention, what I

- claim as new, and desire to secure by Letters Patent, is:
1. In combination, a rose-head in communication with a source of fluid supply, and a removable branching division contrivance therein.
  2. In combination, a rose-head in communication with a source of fluid supply, and a differentiating imperforate division contrivance changeable therein to variably cut off portions of the areal delivery surface thereof from said fluid supply.
  3. In combination, a rose-head in communication with a source of fluid supply, and a removable division contrivance therein consisting of a unitary branched member adapted to vary the areal delivery surface of the rose-head when said division contrivance is changed in position.
  4. In combination, a rose-head in communication with a source of fluid supply, and a removable radiating division contrivance therein reversible in position to selectively cut off determined different sized portions of its delivery area from said source of supply.
  5. In combination, a rose-head in communication with a source of fluid supply, a reversible differentiating division contrivance removably mounted therein, and means for fastening said division contrivance therein to prevent leakage between it and the contacting parts of the rose-head.
  6. In combination, a rose-head, and an imperforate branched division contrivance therein adapted to be positioned to cut off varying areas of the delivery surface of the rose-head from the source of fluid supply thereto.
  7. In combination, a rose-head having a removable base, and a division contrivance removably mounted between said rose-head and base and adapted to variably cut off portions of the delivery-area of the rose-head.
  8. In combination, a rose-head, a removable base therefor having an inlet-port, and a division contrivance mounted removably between said rose-head and base adapted to cut off a portion of the delivery area of the rose-head from said inlet-port.
  9. In combination, a rose-head, a removable base therefor having an inlet-port and a branched division contrivance mounted between said parts, reversible to cut off varying portions of the delivery area of the rose-head from said inlet-port.
  10. In combination, a rose-head, and imperforate recessed means mounted adjustably therein to cut off greater or less segments of the delivery zone of the rose-head.
  11. In combination, a rose-head, a removable base therefor, a division contrivance removably mounted in said rose-head reversibly to variably restrict the lateral delivery to certain segments thereof, said rose-head having an orifice, said division contrivance having a threaded socket in alinement with said orifice, and a screw passed through said orifice into said socket and adapted to fasten the division contrivance to the rose-head to prevent leakage therebetween.
  12. In combination, a rose-head, a removable base therefor provided with an inlet-port, and a division contrivance seated removably and fittingly between the rose-head and said base, said contrivance consisting of a diametral partition for the rose-head having a lateral part extending at a right angle from its middle at one side, said contrivance being reversible in the rose-head to cut off a one-half or a one-quarter segment of the delivery surface thereof from said inlet-port.
  13. In combination, a dome-shaped rose-head, a closure therefor having an inlet-port, and a removable partition fitted between said closure and rose-head, dividing the interspace into unequal compartments, of which one only at a time is in communication with the inlet-port.
  14. In combination, a rose-head provided with numerous delivery orifices, a closure therefor, and a T-shaped division-contrivance mounted between the closure and the rose-head.

Signed at Waterloo, Iowa, this 20th day of April, 1916.

GEORGE COLVIN KENNEDY.
